UNITED STATES PATENT OFFICE

JANE HALE, OF CHICAGO, ILLINOIS

DESIGN FOR A WASH-CLOTH DOLL

Application filed December 13, 1930. Serial No. 37,973. Term of patent 7 years.

To all whom it may concern:

Be it known that I, JANE HALE, a citizen of the United States of America, and a resident of the city of Chicago, in the county of Cook and State of Illinois, have invented a new, original, and ornamental design for a Wash-Cloth Doll, of which the following is a specification, reference being had to the accompanying drawing, forming part thereof.

In the drawing,

Fig. 1 is a front elevation view of a doll

of washcloth material, showing my new design; and

Fig. 2 is a side elevational view thereof.

I claim:

The ornamental design for a washcloth doll, as shown.

Signed at Chicago, in the county of Cook and State of Illinois, this 9 day of December, 1930.

JANE HALE.
